UNITED STATES PATENT OFFICE.

EDWIN HANSALPAKAR, OF CAMPELLO, MASSACHUSETTS, ASSIGNOR TO BROCKTON HEEL COMPANY, INC., OF BROCKTON, MASSACHUSETTS, A CORPORATION OF MASSACHUSETTS.

HEEL-PRESS WITH AUTOMATIC EJECTOR.

1,332,037.

Specification of Letters Patent.

Patented Feb. 24, 1920.

Application filed January 7, 1918. Serial No. 210,662.

To all whom it may concern:

Be it known that I, EDWIN HANSALPAKAR, a citizen of the United States, residing at Campello, in the county of Norfolk and 5 State of Massachusetts, have invented new and useful Improvements in Heel-Presses with Automatic Ejectors, of which the following is a specification.

This invention relates to machines of the 10 type disclosed in my prior Patent No. 1,262,335 granted April 9, 1918, in which newly built heels are placed by an operator who continually builds heels in a position beside the machine and places them therein 15 whenever a sufficient number of such heels have been made. The heels supplied thus to the machine are automatically put under pressure immediately upon being admitted to the machine, are gradually propelled to 20 ward a discharge outlet while being all the time kept under pressure, and are automatically ejected when arriving at the discharge point. As long as they remain in the machine the heels are arranged in tiers, sepa- 25 rated by trays, commonly called boards, and when ejected from the machine, the heels pass into a receptacle and the boards are returned to a point where they can be easily 30 reached by the heel building operator to be taken for use to support another tier of newly built heels.

In the operation of the machine referred 35 to the stack of heels and boards is propelled through a guideway by the action of a table on which the board with its load of heels is placed, which table carries each board with the tier of heels supported thereon to the entrance of the guideway, and adds it to the stack already therein, and in doing so ad- 40 vances the entire stack a distance equal to the combined height of the heels and the thickness of the board, less whatever compres- 45 sion is suffered by the heels due to the resistance of the entire stack to being thus propelled. Such heels, however, may vary considerably in height, some high heels being as much as two, three, or even more, times as high as the lowest heels; and it frequently happens that the operator of the 50 same machine is required to change from one style of heel to another. That is, after completing an order for high heels the op-

erator may be required to build a number of low heels, and the reverse. Thus the length of the steps of progression of the 55 stack of heels in the press may vary at different times, and may be greater or less than the height of the heels next approaching the discharge point. In the machine shown in my aforesaid patent, the ejector is operated 60 once whenever the table is caused to propel the stack in the manner above described, with the result that in consequence of the feeding in of heels higher or lower than those already in the press one of several ob- 65 jectionable results is liable to occur. Either the ejector may remove the board resting on the topmost tier of heels, without removing the underlying heels, or the heels engaged by the ejector may fail to clear the edge of the 70 discharge opening and may be jammed and injured, or a board may fail to clear and so becomes jammed, or two or more boards may be removed at the same time, of which only one can be returned in the desired way and 75 the other falls into the heel receptacle and must be removed by the operator or by some other person, at the cost of an appreciable loss of time.

It is the purpose of the present invention 80 to provide ejecting means which shall be controlled as to its operation wholly by the position of the endmost or top tier of heels in the stack, to operate only when such tier is in the position for discharge, and to op- 85 erate more than once in case the propulsion of the stack caused by introducing a layer of high heels should bring two or more tiers of low heels successively into the discharging position. Thus my invention consists in 90 ejecting means having capability of operating in this manner, and includes the combination of the same in a heel press of the sort indicated; although the invention is not limited to this combination but consists of 95 means and mechanism having the principles above indicated and hereinafter described in detail, for all purposes which the same may be capable of serving.

In the drawings forming a part of this 100 specification,

Figure 1 is a front elevation of a heel press having my invention applied thereto,

Fig. 2 is a plan view of the press.

Fig. 3 is a vertical section of the top part of the press, showing the elements of the combination in greater detail than the same appear in Fig. 1.

5 Fig. 4 is an elevation of the top part of the press as seen from the right hand side of Fig. 1.

10 Fig. 5 is a perspective view of a part of the mechanism embodying my present improvement.

Fig. 6 is a sectional elevation showing the parts above the line 6—6 of Fig. 2.

Fig. 7 is a sectional detail view on line 7—7 of Fig. 2.

15 Fig. 8 is a similar view on line 8—8 of Fig. 2.

Fig. 9 is a perspective view of the entrance end of the guide through which the trays or boards are ejected, illustrating a 20 detail of my invention.

The same reference characters indicate the same parts in all the figures.

In the following description I shall refer to the articles which are treated in the machine as "heels," although actually the same are not complete merchantable heels, but are piles of lifts coated and stuck together with wet adhesive; and I shall designate by the term "boards" the trays on which the heels 30 are laid as soon as they are built, and by which adjacent tiers of heels in the press are separated from one another, these terms being thus used for convenience and without limiting intent.

25 The machine comprises a base 1 and a frame rising therefrom composed of corner posts 2, cross bars 3, and guide strips 4 substantially parallel to the posts fastened to the inner sides of the cross pieces 3, the function of which is to guide the boards loaded with heels and also to apply pressure to the edges of these boards, causing friction which resists their passage through the frame and so requires application of substantial force 40 to advance them to the discharge point. This frame thus provides an extended passageway, preferably vertical in position, in which a stack of boards and intermediate tiers of heels are confined.

45 In the front side of the frame is an opening 5, beside which is mounted a shelf 6, whereon boards are placed singly and allowed to rest while being loaded with heels. Within the frame is a table 7 which 55 normally stands at rest with its upper surface in the same plane with, or slightly below, the supporting surface of the shelf 6. This table is adapted to be elevated by means of a main shaft 8 acting through a 60 worm and a worm wheel 9, to drive a second shaft carrying cranks 10, 10 which are coupled by connecting rods 11, 11 with the table. 12 represents a pulley which is rotated constantly and is loose on the main shaft 8, 65 being coupled therewith from time to time

by the action of the operator who manipulates a handle 13 on a rod 14 to operate a clutch shifter 15 which couples the pulley to the main shaft 8 and thereby actuates the above described mechanism to raise the table 70 and return it. The details of the clutch and the means for coupling it and automatically uncoupling it after the table has made its trip up and back, are fully explained in my prior patent aforesaid, to which reference is 75 directed, and are therefore not shown herein.

At the top of the structure which has heretofore been called the "guideway," and which may also be considered as the holder for the stack of heels, there is an outlet at 80 one side from which projects a spout 16 overhanging the open top of the cage or bin 17, which is mounted on the frame to receive the discharged heels. The guide strips 4 at the side of the frame next to the bin 17 terminate at the height of the entrance to this spout. Above the spout is a discharge guide for the boards comprised by two side bars 18, 19, plates 20, secured to these bars and passing across from one to the other and 85 ledges 21 (Fig. 9) on each of the side bars to support the opposite edges of the board, and substantially in the manner fully disclosed in said prior patent. The outer ends of the bars are connected by a pivot rod to 90 fixed beams 22 which are mounted on the frame and project laterally therefrom as shown in Fig. 1. From the upper plate 20 extensions 23 (Fig. 3) pass, and rest on the topmost board of the stack and are raised as 95 the latter rises, whereby the entrance to this guide is always caused to register with the topmost board when the latter is in position to be discharged. The ledge on the bar 19 terminates short of the outer end of the bar 100 a distance greater than the length of a board, while the ledge on the bar 18 extends nearly or wholly to the end of that bar. This board guide conducts the topmost board over the outlet for the heels and across the 105 bin, and discharges the same into a runway 24 which allows the board to be returned by gravity into a position where they can be 110 reached by the operator. The construction of the board guide, by which this result is obtained is fully set forth in my prior application referred to.

115 The ejector 25 removes the topmost board and the tier of heels directly under the same at each stroke, the board being conducted through the guide and the heels passing over the spout 16 into the bin. This ejector is carried by a slide 26 mounted to move in proper guideways in the under side of the top plate 27 of the frame, and being 120 equipped with a rack 28 meshing with a pinion 29 loosely mounted on a shaft 30, this shaft being driven from the previously described main shaft 8 by a pulley 31 on the latter, a belt 32 and a pulley 33 on shaft 125 130

30. A clutch head 34 is splined to the shaft 30 and is adapted to be coupled with the pinion 29, having a stud 35 arranged to coact with a stud 36 on the pinion (Figs. 4 5 and 6).

As thus far described the machine is substantially the same as shown in my prior patent referred to, having substantially the same construction and mode of operation.

10 The new features in which the invention here claimed consist are as follows:

The shifter for the clutch head 34 is a lever 37 pivoted on a stud 38 and acted upon by a spring 39 which tends always to move 15 the clutch shifter so as to couple the clutch head with the pinion. It is prevented from doing so by a latch 40 which is pivoted at 41 on a bracket 42 fixed to the top of the frame, the toe of the latch normally lying in the 20 way of the clutch shifter, as shown in Figs. 7 and 8. This latch is held by gravity in the position shown, and is returned to that position by gravity after being displaced therefrom. Displacement is effected by a 25 link or finger 43 which is properly engaged with the latch and hangs down therefrom toward the stack, its depending end being retained in position by a guide 44. Preferably connection between this link and the 30 latch is made by forming the link with an opening having substantially the same outline as the cross section of the latch, so that the latter may enter such opening. As the stack rises, the uppermost board, which is 35 designated 45 in the drawings raises the link, which exerts pressure through the lower edge of the opening described on the latch, and so disengages the same from the clutch shifter. Any other mode of connection 40 or engagement between the latch and the link, suitable for the purpose, may be employed. Functionally the link is a latch tripper, and may be so called.

The ejector-carrying slide 26 supports uprights 46, 47 on which is mounted a bar 48 passing over the top plate 27, and carrying two cam members 49 and 50. The cam member 49 is a long strip having inclined cam surfaces 51 and 52 at its opposite ends respectively. The cam member 50 is a wedge block having an inclined cam surface 53, the inclination of which is opposite to the inclination of the cam surface 52. Rigidly attached to the clutch shifter 37 is an arm 54 at a level above the top of the cam strip 49, this arm having a depending stud carrying an antifriction roll 55. This arm 54 is secured upon a block 56 attached to the clutch shifter, and one end of the block 55 55 forms a shoulder or abutment adapted to coact with a latch 57 having a notch 58 to receive this abutment. This latch is connected by a pivot 59 to the top plate of the frame, and is acted on by a spring 60 which 60 urges it toward the abutment 56. Spring 60

is connected at one end to latch 57, and at its opposite end to a stud rising from top plate 27. On the upright or post 47 carried by the slide 26 is a finger 61 in the same plane with the latch 57 and adapted to disengage 70 the latter from the abutment 56.

A weight 62 is connected to a cord 63 which passes over a guide pulley 64 and is connected to the post 47 and thereby to the slide 26; said weight acting to return the 75 slide and the ejector when the clutch has been uncoupled at the end of the ejecting stroke.

The operation of my improved mechanism last described is as follows: When the 80 stack is raised by the operation of the table, the topmost board 45 engages the latch tripper 43 when the topmost tier of heels has reached the level of the discharge outlet. Thereby the latch 40 is tripped and 85 the clutch shifter permitted to couple the pinion 29 to the shaft 30 by means of the clutch head 34, since the clutch shifter has a stud 65 projecting into a groove in the clutch head. The ejector is than caused to 90 travel toward the discharge outlet, pushing the top board into the board guide and the top tier of heels over the spout 16, being provided with a plate 25^a which is wide enough to engage all the heels in the outer- 95 most row of the tier. The ejector is pro- 100 pelled far enough to push the last heels through the outlet, and when it has reached the end of its stroke the surface 53 of the wedge cam engages the stud 55 of the lat- 105 eral arm on the clutch shifter, moving the latter until the clutch stud 35 is disengaged from the clutch stud 36. Thereupon the weight 62 acts to return the ejector to the starting position. At the same time also the 110 latch 57, which I may call the "secondary latch," engages block 56 and acts to hold the clutch out of engagement until the cam strip 49 becomes effective for this purpose. It will be understood that a wide enough 115 space is necessarily left between the cam surface 53 and the end of the cam strip 49 to admit the stud 55, and also that as soon as the ejector slide begins to return, the wedge cam backs away and would permit the 120 clutch shifter to couple the clutch again if no means were provided to prevent this re- 125 sult. The latch 57 is the means for this purpose, and it is so arranged that its latching shoulder will overlap, so as to engage, 120 the abutment 56 before the clutch shifter has been displaced far enough to be ar- 125 rested by the main or primary latch 40, as this arrangement is necessary because the primary latch must be so placed as to hold the clutch sleeve well clear of the pinion so that there will be no possibility of the stud 35 striking the stud 36. But it is not pos- 130 sible by the action of the wedge cam 50 alone to move the clutch shifter far enough

for this purpose, because the slide 26 stops as soon as the clutch has been moved far enough for the stud 35 to slip past the end of the stud 36, the slide not having sufficient momentum to carry it farther, on account of the resistance to its further movement due to its own friction, to the resistance of the board being propelled by the ejector, and to the backward pull of the weight 62. 5 Owing to the nature of the material of which the clutch is made, its elastic compressibility and the wearing away of the contiguous corners of the studs 35 and 36, these studs will become disengaged so that 10 the former will slip past the latter before they have become separated so far as to pass entirely clear of one another without striking, and thus before the clutch shifter has been displaced far enough to become locked 15 by the primary latch. Hence if it were not for the secondary latch, the effect would be that the wedge cam would cause stoppage of the ejector, allowing it to be withdrawn by the weight until the clutch head 34 had completed 20 part of an idle revolution, whereupon the clutch would again engage, and the slide, with the ejector would then continue to vibrate back and forth in the same spot without ever being allowed to return to 25 starting position, as long as the driving means remains in operation. The function 30 of the secondary latch therefore is to hold back the clutch stud 35 to a path in which, although it may strike the end of the stud 35 in passing, it will not positively engage 35 it, and hence will not drive the pinion. The ends of these studs may, if necessary, be formed otherwise than square with their 40 engaging sides; that is, such ends may be beveled toward the contacting sides whereby to insure passing of one by the other without positive engagement under the conditions last described.

Immediately after the slide 26 has commenced 45 its return stroke, under the action of weight 62 when the clutch has been released, the inclined surface 52 on the cam strip 49 engages the stud 55 and moves the clutch shifter still farther, to the position 50 in which it will permit the latch 40 to become engaged in the manner shown in Figs. 7 and 8, and the secondary latch is so formed as to permit such further movement. In the construction illustrated the 55 notch 58 in this latch which receives the abutment block 56 is enough wider than such block for the purpose. The finger 61 acts when the slide has finished its return stroke, to strike the secondary latch and displace 60 it out of the way of the abutment 56 so that this latch no longer opposes coupling of the clutch. This is the normal condition 65 of the machine. It results after the ejector has completed its operation, and persists until the stack has been further raised far

enough to disengage the latch 40 and effect renewed operation of the ejector in the manner already described.

From the foregoing it will be appreciated that when the ejector reaches the end of its 70 retracting stroke, the only impediment to a second coupling of the clutch is the main latch 40. If during the cycle of movements of the ejector, the stack should continue to rise until the board distinguished in the 75 drawing as 45^a becoming in its turn the top-most board, has reached the position occupied by the board 45 when the operation was started, the latch is withheld from locking the clutch shifter, and the same is thereby 80 left free to couple the clutch again as soon as the finger 61 has disengaged the secondary latch. This occurs after the end of the cam strip 49 has passed away from the stud 55. In this way a second operation 85 of the ejector is initiated, with the effect of ejecting the second heel board and the second tier of heels. The same effect occurs, but with more or less intervening delay, in case the main latch should have locked the 90 clutch shifter at the end of the first return stroke, but the stack should continue thereafter to rise. It will be noted from Figs. 7 and 8 that when the latch 40 is disengaged from the clutch shifter by being raised, the 95 clutch shifter passes under it. The latch is freely pivoted and is able to drop by gravity upon the clutch shifter, and rest there, after the topmost board has been displaced, so that it may drop in back of the clutch 100 shifter and lock it, as soon as the clutch shifter has been displaced by the action of the cams already described.

In the machine as I have built and operated it, the drive for the ejector slide is 105 so proportioned that the slide may make between two and three complete cycles, while the table makes one cycle; and it is within my contemplation to design the driving mechanism to effect three or more cycles 110 during the same time. It will be seen that whatever the capacity of the driving mechanism is, the actual number of cycles of the ejector is controlled entirely by the position of the topmost board in the stack and the 115 height of the heels. The operation of the ejector being as soon as the upper tier of heels has come to register with the discharge opening. The guide for the boards is always registered with the topmost board, 120 whatever may be the actual height of the heels in the tier next under such board because the extensions 23 from the board guide rest on the topmost board, and the pivot mounting for the outer end of said 125 guide allows such extensions and the entrance to the guide to rise with the topmost board. It follows then that, whatever may be the ratio of the height of heels in the topmost tier or tiers to the amount of 130

travel given the stack by the heels last added thereto, all of the boards ejected during each cycle of the propelling table are delivered to the proper depository, and all of 5 the heels are properly delivered. It also follows that none of the heels will be injured by striking the lower edge of the outlet, because the trip mechanism is so designed as not to throw the ejector into gear until the 10 highest heels treated in the machine have advanced far enough to clear the outlet. There is no opportunity for a premature operation of the ejector; or for more than one board and one tier of heels to be ejected 15 at the same time; or for the heels and boards to be delivered anywhere except to the proper depositories.

Another feature of the invention consists in a modification in the construction to prevent 20 boards and heels below the topmost tier being carried through the outlet by adhering to the heels being ejected and to one another when low heels are brought to the discharge point under propulsion from a 25 charge of high heels, and also to insure against the heels being obstructed and jammed when a change in atmospheric conditions, such as of humidity or of temperature, increases the height of the heels from 30 that for which the machine is adjusted. The outlet for the heels is determined by the outer termination of the guide strips 4 on the outlet side. According to my present invention such strips 4 are arranged to 35 terminate at the point 4^a, which is at a level well below the position of the second board of the stack. Thereby, if it should happen that atmospheric conditions should cause the 40 heels to swell, or to dry less slowly, so that they are higher than contemplated, the heels being ejected will be sure to pass through the outlet. At the same time the next to the top board is prevented from being carried along with the uppermost tier 45 of heels by a stop 66 which is fixed to one of the side bars of the board outlet guide and projects downward therefrom below the level of 4^a. This stop thus crosses the plane of the second board from the top and is in 50 the path of one edge of that board, but it is so far to one side of the heels that it does not interfere with the free ejection of the latter. The feature last described is not a condition limiting the use of the portion 55 of the invention first described, but is an auxiliary feature serving a useful purpose when conditions are more or less abnormal.

What I claim and desire to secure by Letters Patent is:

1. In a heel pressing machine having means for holding heels and boards or trays in tiers in a stack, means for adding successive tiers and boards to the stack and propelling the stack, and an ejector for dis-

charging boards and heels; a control means for said ejector for setting the same in operation controlled by the position of a certain tier of heels in the stack.

2. In a heel pressing machine having 70 means for holding heels and boards or trays in tiers in a stack, means for adding successive tiers and boards to the stack and propelling the stack, and an ejector for discharging boards and heels; a means for setting the same in operation under the control of the endmost board in the stack, said means being successively operative by other boards upon arrival of the latter in a given position. 75

3. In a heel pressing machine having a guideway adapted to contain a stack of heels arranged in tiers and boards between adjacent tiers of heels, a pusher for adding heels and boards successively to the stack 85 and propelling the same through said guideway, the machine having separate outlets for boards and heels at the end of the guideway remote from said pusher; an ejector movable across the stack toward said outlets and constructed to propel at the same time the endmost board and the next adjacent tier of heels through said outlets, normally inoperative actuating means for said ejector, and devices operated by progression of such endmost board for setting 90 said actuating means in operation. 95

4. In a machine as set forth in claim 3 the actuating means for the ejector characterized by a clutch, and a spring tending 100 to put said clutch in the coupled condition, and the devices controlled by the board characterized by a latch for holding said clutch uncoupled, and means by which the progression of the board displaces said latch 105 and allows the clutch to be coupled.

5. In a heel pressing machine, the combination with a guideway for heels and boards, of a reciprocative ejector mounted to travel across said guideway, and toward 110 which a stack of boards and heels is propelled through the guideway, driving mechanism for actuating said ejector including a disconnectible clutch, potentially active means for retracting the ejector upon disconnection of said clutch, a clutch shifter, means tending always to actuate said shifter so as to couple the clutch, a stop for preventing actuation of the shifter by said means, and a trip controlled by the advancing 115 stack for disabling said stop.

6. A machine according to claim 5 and including means arranged to travel with said ejector and to cause movement of the clutch shifter for uncoupling said clutch 125 when the ejector reaches the end of its operate stroke.

7. In a machine of the character described, an ejector, a reciprocative slide carrying the same, a rack and pinion for driving said 130

slide in one direction, a disconnectible clutch for actuating said pinion, a potentially active yielding element for returning the slide when said clutch is disconnected, 5 means controlled by advance of the articles treated in the machine for automatically causing connection of said clutch, and means whereby the slide disconnects the clutch at the end of its stroke in one direction.

10 8. The combination with a reciprocating slide, of a rotating driving element for moving the same in one direction, a yielding potentially active actuator for moving it in the opposite direction, a disconnectible clutch associated with said driving element, a clutch shifter connected with said clutch, a spring acting on said clutch shifter tending to connect the clutch, a displaceable stop for holding the shifter in the position 15 for uncoupling the clutch, a cam connected with the slide having a surface arranged to act on said clutch shifter and disconnect the clutch at the end of its movement in one direction, a second cam for further moving 20 the clutch shifter during the movement of the slide in the opposite direction, and a secondary latch for holding the clutch shifter in the position to which it is moved by the first cam during the period intervening un- 25 til it is acted upon by the second cam.

9. The combination with a backward and forwardly moving traveler, a rotating driving element for rotating the same in one direction, a disconnectible clutch for transfer- 30 ring power to said driving element, a potentially active yielding driver for moving said traveler in the opposite direction, a shifter for said clutch, a spring acting on said shifter tending to couple the clutch, a main 35 latch for holding the shifter in the clutch-

uncoupling position, means carried by the traveler for uncoupling the clutch and including two elements, one of which acts during the movement of the traveler in the first direction and the other acts during its 45 movement in the opposite direction, and a secondary latch for holding the clutch shifter in the uncoupling position during the interim between the action of the first element and of the second element respectively. 50

10. The combination with a backward and forwardly moving traveler, a rotating driving element rotating the same in one direction, a disconnectible clutch for transmitting 55 power to said driving element, a potentially active yielding driver for moving said traveler in the opposite direction, a shifter for said clutch, a spring acting on said shifter tending to couple the clutch, a main 60 latch for holding the shifter in the clutch-uncoupling position, means carried by the traveler for uncoupling the clutch and including two elements, one of which acts during the movement of the traveler in the first 65 direction and the other acts during its movement in the opposite direction, the second element being operative to move said shifter into the position wherein it becomes locked by the primary latch, a secondary 70 latch for holding the clutch shifter in the uncoupling position during the interim between the action of the first element and of the second element respectively, and means carried by the traveler for disengaging the 75 secondary latch at the end of the return movement of the traveler.

In testimony whereof I have affixed my signature.

EDWIN HANSALPAKAR.
